AIR TREATING MECHANISM

John D. Landerman, Boston, Mass.

Application September 18, 1933, Serial No. 689,829

4 Claims. (Cl. 261—90)

This invention relates to air treating mechanism and the object is to provide an efficient and compact mechanism of this kind which, though not necessarily limited thereto, is particularly suitable for use as a portable or semi-portable unit for domestic use.

My invention may be well understood by reference to the following description in connection with the illustrative embodiment thereof shown, by way of example, in the accompanying drawings, wherein:

Fig. 1 is a vertical section through the mechanism with various parts broken away;

Fig. 2 is a similar plan section with parts broken away;

Fig. 3 is a broken section on the line 3—3 of Fig. 2;

Fig. 4 is a section on the line 4—4 of Fig. 4; and

Fig. 5 is an enlarged section on the line 5—5 of Fig. 2.

Referring to the drawings, the device shown is organized in a suitable housing 7 which may be formed as or received within any suitable ornamental article of furniture. The lower portion provides a water tank which may be permanently or temporarily connected at 11 with a source of water supply, a valve controlled by a float 13 providing for maintaining a constant level of water in the tank. I may also provide a funnel-like opening 15 at the side of the housing which is exposed when the door 21, herein after referred to, is open to permit the tank to be filled from a pitcher or the like. Refrigerating coils 17 and a heater 19 may be provided for controlling the temperature of the water as desired. In the bottom of the tank there is preferably formed a sump 21 in which solid matter may collect provided with the clean-out opening 23.

In the upper part of the casing there are provided opposing openings 25 and 26 providing between them an air passage. The opening 25 may be normally closed by the hinged door 27 comprising inner and outer perforated plates 29 receiving between them a body of suitable porous material such as a packing of steel wool, the door thus consisting essentially of a porous slab constituting an air filter. Mounted between the openings on a stirrup 33 I have herein shown an electric motor 35 of the double shaft type, that is, having its rotor shaft projecting at both ends. The end adjacent the door carries a rotary fan 37 adapted to draw air through the filter which constitutes the door into the air passage for dis-

charge through opening 26, while the opposite end of the shaft carries suitable water dissipating means.

In the embodiment of the invention herein shown the water dissipating means is multiple. I have herein shown as secured on the motor shaft a hub 39 carrying a spider 41 which supports inner and outer drums 43 and 45, respectively. The inner drum 43 may have a diameter at least substantially as great as the case of the motor 35 so as not to be shielded by the same from the current of air from the fan. This drum has a suitable absorbent wall and is herein shown as consisting of a body of felt or similar absorbent material 47 received between two porous cylindrical plates 49. The outer drum 45 may be formed of sheet metal which has its surface suitably formed to dissipate water. Herein I have shown parts struck up therefrom to form openings 51, the material displaced from the openings forming vanes 53 which are inclined to the radial, as best shown in Fig. 5, and are bent upwardly along base lines diagonal to the elements of the cylinder, as best seen in Fig. 2, so that in rotation of the drum they tend to force fluid with which they come in contact toward the opening 26.

A suitable hood or casing 55 overlies the motor and the parts carried thereby and it is continued, as indicated at 57 at the right of Fig. 1, completely to encircle the drums 43 and 45. This part of the housing may be lined at 59 with lead to obviate objectionable noise and the lower part thereof is provided with a drain 61 to return any accumulated liquid water to the tank.

Between the drums and the opening 26 and closely adjacent to the former I provide scrubbing plates 63 preferably of the form best seen in Fig. 2 defining zigzag or tortuous passages therebetween. In the operation of the device the blades 53 forcibly drive the air and water fog against these plates. They not only serve as baffles to eliminate liquid water as such from the air stream but act to thoroughly scrub and wash the air. The plates are constantly wet and the air and water forcibly worked thereupon to provide a scrubbing action to clean the air. It is the fact that the mere mixing of water spray and air, while it will humidify the air, will not wash solid particles from the same. This requires a scrubbing action which is efficiently obtained in the present instance by the forcible projection of the water against and through the scrubbing plates 63. Water deposited on the plates gravitates along the same to the gutter 55.

65 beneath them from which it may return through drain 67 to the tank. The two rotary drums 43 and 45 are located, as seen in Fig. 1, above the level of the water 5 in the tank and do not make contact therewith. Water may be supplied to their surfaces through power taken from the shaft of the motor 35, and herein the hub 39 has formed as a portion thereof a belt pulley 69 with which cooperates 10 a companion pulley 71 carried at the end of an arm 73 depending from the stirrup 33. The lower pulley 71 is located beneath the surface of the water in the tank. About the pulley is trained a belt conveyor 75. I name it thus in 15 the present instance in a descriptive sense, since in the embodiment shown it functions both as a driving belt to transmit power and as a direct conveyor of water. Thus, referring to Fig. 1, a suitable pump 77, unnecessary to illustrate in 20 detail, is driven from the shaft of the pulley 71. The intake of the pump is to the tank and the discharge to the pipe 78 preferably leading to the space between the drums 43 and 45. Herein I have shown a spray nozzle 79 located in this 25 space and discharging against a fixed baffle 81, thus providing for the delivery of water in finely divided form between the two drums, to find its way to the surfaces of both of them. Apart from the action of the pump, water is also delivered to the drums by the direct action of the 30 belt acting as a conveyor. The belt 73 (see Figs. 2 and 3) is herein shown as enclosed by a two-part housing 83, the parts being hinged together at 85 and the hinge line being covered by the 35 plate 87 to prevent egress of water therethrough. At the upper end of the housing and at the side toward which the belt moves, it is provided with the enlargement 89 which, in cooperation with the baffle wall 91 extending adjacent the top of the belt, forms a receptacle. Water thrown from 40 the belt as its direction of motion is reversed is thrown into this receptacle or against the walls of the housing to drain along said walls to the receptacle. A hole 93 leads from the bottom of the receptacle to a nozzle 95, which, as seen in 45 Figs. 2 and 1, projects forwardly into the interior of the drum 43. This nozzle is provided with holes 97 through which the water may drain from the receptacle and drip onto the inner wall 50 of the absorbent drum 43.

In the operation of the device, water is finely broken up and thoroughly commingled with a stream of filtered air drawn by the fan 37 through the door 27 and discharged about the 55 motor casing. The cooperative and reciprocal action of the two drums is particularly effective in bringing the water into intimate contact with the air while the forcible projection of the water fog and air against the scrubbing plates 63 by 60 means of the diagonally disposed blades 53 effects a thorough scrubbing of the air as it passes through these plates while eliminating surplus water therefrom. Air properly filtered, washed and tempered is thus delivered through the latter opening. If the device is stopped and the spraying action effected by the pump 77 thus 65 intermitted, any water accumulated in the re-

ceptacle 89 will drain therefrom through the nozzle 95 to the absorbent wall of the drum 43, which is thus maintained in a moist condition ready for immediate action.

A pipe coil 99 may be provided traversing the baffles 63 through which a refrigerant or a heating medium may be circulated to cool the passing air. The baffles serve also as conducting fins for the pipe of which this coil is formed.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. In a device of the class described an air conduit, a drum rotating therein having a foraminous wall and provided with oblique blades, means for delivering water to said wall from a location remote from the drum to be broken up and centrifugally discharged thereby and tortuous scrubbing plates adjacent an end of the drum against which the air and water fog are forcibly driven by said blades and through which the washed air is delivered.

2. In a device of the class described an air conduit, a series of concentric foraminous drums and an external drum surrounding the same having a sheet metal cylindrical wall with parts struck up therefrom along oblique lines to provide openings and exterior blades, said drums rotating as a unit, means for delivering water from a location remote therefrom to said drums to be broken up and centrifugally discharged thereby and tortuous scrubbing plates adjacent one end of the drums against which the air and water fog are forcibly driven by said blades and through which the washed air is delivered.

3. In a device of the class described an air conduit, a drum rotating therein having a foraminous wall and provided with oblique blades, means for delivering water to said wall from a location remote from the drum to be broken up and centrifugally discharged thereby and tortuous scrubbing plates adjacent an end of the drum against which the air and water fog are forcibly driven by said blades and through which the washed air is delivered and a pipe for heat exchange fluid passing through said plates transversely to the air discharging passages therethrough.

4. A device of the class described comprising an air conduit, a rotating device therein for breaking up and discharging centrifugally across the air stream water delivered thereto, means for delivering water to said device from a remote point, an encircling drum rotating with said device having a multiplicity of oblique blades and tortuous scrubbing plates adjacent an end of said drum against which the air and water fog are forcibly driven by said blades and through which the washed air is delivered.

JOHN D. LANDERMAN.
